UNITED STATES PATENT OFFICE.

CHARLES E. RENSHAW AND ELLIS C. HEALY, OF EAST ORANGE, NEW JERSEY,
ASSIGNORS TO NEWMAN CLOCK COMPANY, INC., OF NEW YORK, N. Y., A COR-
PORATION OF NEW YORK.

YARD POST.

1,407,817.

Specification of Letters Patent. Patented Feb. 28, 1922.

Application filed April 8, 1919. Serial No. 283,591.

To all whom it may concern:

Be it known that we, CHARLES E. REN-
SHAW and ELLIS C. HEALY, both citizens of
the United States, residing at East Orange,
5 in the county of Essex and State of New
Jersey, have invented certain new and use-
ful Improvements in Yard Posts, of which
the following is a full, clear, and exact de-
scription.

10 The invention which constitutes the sub-
ject-matter of this application has to do with
mechanism adapted to be connected to a
valve for controlling the access to a record-
ing key. That is to say, when the valve is
15 in its normal position access may be had to
a recording key but if the valve is not in its
normal position the key is rendered inacces-
sible. As these valves (or "stations") are
equipped with a key a time imprint may be
20 made on a record dial of a watchman's
clock which indicates the time at which the
station was visited by the watchman. So
long as these imprints are made at the re-
quired intervals, as shown by the record dial,
25 it is a sure indication that the valves at these
particular times were in normal position.
But if the imprint of a certain station is
omitted from the record dial it would be an
equally sure indication that the key at that
30 station was inaccessible and therefore that
valve was not in normal condition. Of
course, if it is a part of the watchman's
duty to move the valve from its abnormal to
its normal position he could then make the
35 imprint. In any event, the device will have
served its purpose.

Referring to the drawings:

Figure 1 is a partly sectional view of the
upper portion of an indicator post or yard
40 valve equipped with supervisory mecha-
nism, the receptacle thereof being in section.

Fig. 2 is a section, through the receptacle
containing supervisory mechanism, taken at
right angles to that of Fig. 1.

45 Fig. 3 is a horizontal section taken
through that portion of the yard post con-
taining the target.

Figs. 4 and 5 are views similar to Figs. 1
and 2 illustrating a slightly modified con-
50 struction.

The supervisory mechanism herein illus-
trated, described and claimed is designed to
be employed in connection with an indicator
55 post or yard valve which controls a spring-
kler system located in an adjacent building.

The indicator post is composed of two sec-
tions 10 and 11 which telescope with each
other and are relatively adjustable. The
section 10 is fixed upon and supported by
the valve 12 which is to be controlled by the 60
device. Superimposed upon the upper sec-
tion 11 is a cap 13 secured to the section 11
by means of bolts 14, the screw-threaded
ends of which engage with corresponding
screw threads tapping in the upper section 65
11. Rotatably mounted within the cap 13
is a target screw 15 which is held from lon-
gitudinal movement by means of the lock nut
16 under the cap and the shoulder 16^a mount-
ed above the cap. There is provided a 70
wrench member 17 having a rectangular
socket in the lower side thereof engaging
with corresponding member 18, which pro-
jects upwardly from the target screw 15.
The wrench member 17 is held in engage- 75
ment with the outwardly projecting mem-
ber 18 by means of a screw 19 passing
through the wrench member 17 into engage-
ment with said member 18. The lower end
of the target screw is provided with a rec- 80
tangular socket which engages with the up-
per end portion of the valve stem, which we
have designated by the reference numeral
20. The lower end of this valve stem 20 is
likewise provided with a socket member 21 85
which engages with the upper end of corre-
spondingly shaped member 22 constituting
a part of the valve 23. In screw-threaded
engagement with the target screw 15 is a
target 24. The target is provided with one 90
or more grooves 25 in the side thereof which
engage the lugs or flanges 26 on the casting
11. The target may be moved longitudi-
nally by turning the target screw, but is pre-
vented from rotating about its axis by the 95
grooves 25 and lugs 26. The target screw is
provided with a bearing 27 upon which is
pivoted or journaled a rod 28.

Except for the provision of the bearing 27
and the rod 28 in the shape of a turn-buckle, 100
all of the mechanism above described is of
conventional form and we make no claim
thereto except as it forms or constitutes a
part of the combination of the improve-
ments which we will now proceed to describe: 105

The rod 28, as previously stated, is in the
form of a turn buckle to enable an adjust-
ment of its length whenever that is desired.
The lower end of this rod is provided with
a laterally projecting stud 29 which passes 110

through a slot 30 in the casting 11 and also a slot 31 in the container 32, which container is rigidly secured to the casting 11. This stud passing, as it does, into the interior of the receptacle or container 32 engages with the vertically movable slide member 33 which is provided with a lug 34 thereon which is adapted to engage with the arm 35 of a bell crank lever and is adapted to move said lever about its pivot 36. The other arm 37 of the bell crank lever is connected at 38 to a flexible member 39 upon the other end of which is provided a watchman's key 40. This flexible member 39 is concealed within a tubular member 41, the end of which is provided with an outwardly flaring portion 42, so that when the watchman's key is moved inwardly from the position shown in Fig. 1, it is rendered inaccessible. And it may be stated in passing that slide member 33 is held in its movable position by means of the guides 43.

Referring to the modified form of the invention shown in Figs. 4 and 5, it will be noted that the bell crank lever 37 is pivotally connected to one end of a link 44, the other end of which is pivoted to a relatively short arm 45 fixed upon a rotatable shaft 46. This shaft 45 is further provided with an arm 47 to the outer end of which a key chain 48 is attached, the lower end of said key chain being provided with a watchman's key 49. From the foregoing it will be seen that when the vertically slidable member 33 is moved upwardly it cams the bell crank lever 35-37 around its pivotal point 36, moving the link 44 upwardly, which, in turn, imparts a clockwise movement through the arm 45 and the shaft 46 to the arm 47. This causes the outer end of arm 47 to which the key chain is attached to be moved upwardly thereby drawing the key into the receptacle to prevent its use when the parts are in the dotted line positions illustrated in Fig. 5.

The receptacle 32 is secured to the section 11 of the indicator post by means of suitable screws 50 entering bosses 51 from the interior of said receptacle. The receptacle is provided with a removable partition 52 and a removable cover 53, the latter being normally under lock and key. The partition 52 divides the receptacle into two compartments 54 and 55 in the former of which the key 40 is adapted to be connected to the arm 37 as illustrated in Figs. 1 and 2 and in the latter of which the key 49 is adapted to be connected to the arm 47. Suitable bearings are provided in the partition, front cover 60 and back plate of the receptacle for the shafts 36 and 46.

The operation of the device will be clearly understood from the above description, but it may be remarked that with the form of the bell crank lever 35-37 coupled with its

relationship to the slide 33 a slight movement imparted to the valve stem will have a multiplying effect upon the movement of the key. Furthermore, this movement only continues for the first few revolutions of the valve stem; that is to say, until the arm 35 is substantially in vertical position as this position of the arm enables the stud 34 to continue its movement without effecting in any perceptible way the movement of the said arm 35.

It will be noted that the housing 32 carries a pair of pins which extend into the slot 30, thereby forming a means for correctly positioning the mechanism within said housing with respect to the operating mechanism 29 etc.

What we claim is:—

1. A yard valve provided with a stem, a target mounted upon said stem and adapted to move rectilinearly when the latter is rotated, in combination with recording instrumentalities connected to said target normally accessible for making a record, and means for rendering said instrumentalities inaccessible when a few revolutions are imparted to said stem to move the valve from normal position.

2. A yard valve provided with a stem, a target movable longitudinally of said stem when the latter is rotated, a casing surrounding said stem and target, supervisory mechanism connected to the outside of said casing, and means connected to said target and to said mechanism for actuating the latter when the stem is moved from normal position.

3. A supervisory mechanism for valves comprising in combination, a yard valve provided with a stem, a stationary casing surrounding said stem, a housing secured to the exterior of said casing, a watchman's key, and means controlled by said stem and comprising an element extending from the interior of said casing into said housing for moving said key to an inaccessible position.

4. A supervisory mechanism for valves comprising in combination, a yard valve provided with a stem, a stationary casing surrounding said stem, a housing secured to the exterior of said casing, a rectilinearly slideable member mounted within said housing, means connecting said stem and member whereby movement of the former causes movement of the latter, a manually operable recording device, and means controlled by said member for controlling the operativeness of said device.

5. A supervisory mechanism for valves comprising in combination, a yard valve provided with a stem, a stationary casing surrounding said stem, a housing secured to the exterior of said casing, an element within said casing and connected to said stem to be moved rectilinearly on movement of said

- stem, a rectilinearly slidable member mounted within said housing, means for transmitting movement of said element to said member, a manually operable recording device, 5 and means controlled by said member for controlling the operativeness of said device. 6. A supervisory mechanism for valves comprising in combination, a valve provided with a rotatable stem, a nut cooperating with 10 said stem and constrained against rotation, a rectilinearly movable member connected to said nut to be operated thereby, a pivoted arm operable by movement of said member, and a watchman's key connected to said arm. 15 7. A supervisory mechanism for valves comprising in combination, a valve provided with a rotatable stem, a nut cooperating with said stem and constrained against rotation, a casing surrounding said stem and 20 nut, a housing secured to the exterior of said casing, a member mounted for rectilinear movement within said housing, means connecting said nut and member whereby actuation of said nut causes actuation of said 25 member, an arm pivotally mounted within said housing, and a watchman's key controlled by said arm. 8. A supervisory system for valves comprising in combination, a valve provided 30 with a stem, a casing surrounding said stem and provided with a slot, a housing secured to the exterior of said casing, manually operable recording means, mechanism within said housing for controlling the operativeness of said means, means operatively connected to said stem and mechanism and extending through said slot, and means carried by said housing and extending into said slot for correctly positioning said mechanism with respect to its operating means. 35 9. A supervisory mechanism as defined in claim 3 in which the casing and housing are provided with cooperating means for correctly positioning the mechanism within the housing with respect to its operating means. 40 10. A supervisory mechanism as defined in claim 4 in which the casing and housing are provided with cooperating means for correctly positioning the mechanism within the housing with respect to its operating means. 50 11. A supervisory mechanism as defined in claim 5 in which the casing and housing are provided with cooperating means for correctly positioning the mechanism within the housing with respect to its operating 55 means.

In testimony whereof we affix our signatures.

CHARLES E. RENSHAW.
ELLIS C. HEALY.
